UNITED STATES PATENT OFFICE.

THOMAS W. PORTER, OF ORONO, MAINE.

DESIGN FOR A REIN-HOLDER.

SPECIFICATION forming part of Design No. 32,395, dated March 27, 1900.

Application filed December 28, 1899. Serial No. 741,869; Term of patent 7 years.

To all whom it may concern:

Be it known that I, THOMAS W. PORTER, a citizen of the United States, residing at Orono, in the county of Penobscot and State of Maine, have invented and produced a certain new and original Design for Rein-Holders; and I do declare the following to be a full, clear, and exact description of the invention, such as will enable others skilled in the art to which it applies to make and use the same.

The invention relates to a new and original design for a rein-holder; and it consists of a design of the configuration shown in the accompanying drawing, in which I have represented my invention in perspective.

The leading feature of the design comprises the rectangular solid plate 1, having on its

inner side and at its ends rectangular boxes 2 and intermediate its ends an inwardly-projecting stud 3, while from its outer side and at its lower end projects outwardly and thence upwardly a hook 4, the upper end of which extends inwardly toward the body 1 and thence outwardly and terminates in a knob 5.

What I claim is—

The design for a rein-holder, substantially as herein shown and described.

In testimony whereof I have hereunto set my hand in presence of two subscribing witnesses.

THOMAS W. PORTER.

Witnesses:

BENJAMIN F. SMALL,
CLARENCE SCOTT.
